PROCESS AND APPARATUS FOR FRACTIONATING PETROLEUM

William W. Lowe, Westfield, N. J., and Henry N. Lyons, Okmulgee, Okla., assignors to Doherty Research Company, New York, N. Y., a Corporation of Delaware

Application May 21, 1924. Serial No. 714,795

11 Claims. (Cl. 196—49)

This invention relates to the production of merchantable products from crude petroleum.

It is well known that at present a common method of treating crude petroleum oils comprises fractionating the crude by passing it through a battery of stills in series, each successive still in the series being kept at a higher temperature than the preceding one. This fractionating process yields gasoline, kerosene, gas oil, lubricating oils and fuel oil. However, the gas oil is now commonly cracked for gasoline, and the lubricating distillate is commonly rerun and sometimes cracked. Moreover, the gasoline obtained from cracking the gas oil, commonly 10 needs to be rerun. The rerunning of the gasoline and lubricating distillates is expensive in both fuel and labor while the first cost as well as interest and upkeep charges are also all high.

It is the primary object of the present invention to device a process for distilling crude petroleum and an apparatus for practising the same whereby the crude shall be converted into marketable products at better commercial advantage than is now the case.

A second object of the invention is to greatly reduce the amount of fuel required in the complete process of making marketable products from a given crude oil.

It is one of the advantages of the present invention that it produces several products including gasoline without the necessity of rerunning either.

Further objects and advantages of the present invention will be apparent to those skilled in the art from the following detailed description taken in connection with the accompanying drawing, in which

The figure is an illustration partly diagrammatic in character of an apparatus according to the invention and adapted for carrying out the process of the invention.

In the drawing 10 is a pipe through which cold crude is introduced into the system. Pipe 10 connects with a heat interchanger 12 through which the crude passes and in which the crude is heated by thermal heat units derived from hot fuel oil being discharged from the system. The preheated crude from heat interchanger 12 passes through pipe 14, pump 16 and pipe 18 to 45 topping tower 20 within which the crude is intimately mixed with liquids, vapors, and gases from a pressure cracking operation constituting a subsequent step of the process. The heat obtained by the crude from heat interchanger 12 50 added to that delivered to the crude in topping

tower 20 by the pressure distillate drives off the light gasoline from tower 20 through pipe 22 to condenser 24. Topped crude and heavy ends of pressure distillate pass off at the bottom of tower 20 through pipe 26, trap 28, pipe 30 and 60 tank 32 to pump 34. Pump 34 forces the topped oil and heavy ends through pipe 36 to pipe still 38. Still 38 is heated by furnace 40 preferably of the oil burning type. In still 38, the oil is heated to the temperature necessary to vaporize 65 the gas oil fraction of the crude. This temperature is of course, sufficient to vaporize also heavy gasoline and kerosene. The oil and vapors from still 38 pass through pipe 42 into separator 44 where the fuel oil separates from the vapors of 70 heavy gasoline, kerosene and gas oil. The vapors in separator 44 pass off at the top thereof through pipe 46 while the liquid fuel oil passes off at the bottom through pipe 48 to heat exchanger 12 whence it passes to storage through pipe 50. 75

Vapors from separator 44 pass through pipe 46 to fractionating tower or bubble cap column 52 where the heavy gasoline is separated from the gas oil and kerosene. Vapors of heavy gasoline from tower 52 pass out at the top of this tower 80 through pipe 54 to condenser 56. Liquid gas oil and kerosene leave tower 52 at the bottom of the tower and pass through pipe 58, trap 60, pipe 62 and tank 64 to pump 66. Pump 66 forces the gas oil and kerosene through pipe still 68 85 and pipe 70 to fractionating tower or bubble cap column 72. In passing through still 68 the oil is heated to the temperature necessary to vaporize the kerosene fraction but as little as possible of the gas oil fraction. The kerosene vapors 90 pass out at the top of tower 72 through pipe 74 to condenser 76. Vapors of gas oil are thrown back into tower 72 and pass out of the bottom of tower 72 in liquid form and then through pipe 78, trap 79, pipe 80 to tank 82. From tank 82 95 gas oil is forced by pump 84 through pipe 86 to a pipe still 88, heated by furnace 89. In still 88 the gas oil is heated under pressure to cracking temperature but the oil is forced through the coils of the still at a rate preventing any substantial cracking in the still. The oil passes from still 88 through pipe 90 to a cracking and separating chamber 92 under the same pressure as still 88 and within which cracking occurs forming vapors of pressure distillate, gases and heavy 100 liquid bottoms. Vapors and gases from chamber 92 pass out at the top of this chamber through pipe 94 to the topping tower 20. In pipe 94 is a pressure reducing valve 96 for maintaining the desired pressure on chamber 92 and still 88. A 110

by-pass 97 is provided between pipes 94 and 22 and three hand valves 98, 98, 98 are so placed that vapors from chamber 92 may be sent directly to condenser 24 if desired.

5 Furnace 89 for still 88, as well as furnace 40 of still 38, are preferably fired with fuel oil, at least in great measure. Uncondensable gases passing through condensers 24, 56 and 76 may also be used in furnaces 40 and 89 insofar as they 10 are not more valuable for the manufacture of by-products than for fuel. Still 68 is not separately fired but is heated by gases delivered to it from stills 38 and 88 through flues 100 and 102 respectively. After passing through still 68 the 15 flue gases pass off through stack 104.

The operation of the apparatus according to the invention will be apparent to those skilled in the art from the foregoing description. For 20 convenience of reference, the method of operation is summarized as follows:

Incoming cold crude petroleum is preheated by heat interchange with outgoing hot fuel oil. The preheated crude then goes to a topping tower where it is mingled with highly heated vapors 25 of pressure benzine derived from a subsequent step in the process. In the topping tower, light gasoline is vaporized and driven off to a condenser. Material not vaporizing in the topping tower is heated in a still to a temperature high 30 enough to vaporize gas oil and lighter fractions. The vapors mixed with unvaporized fuel oil pass from the first still to a separator where the fuel oil is thrown out of the vapors and passes to the heat interchanger for preheating the incoming crude. Vapors from the separator pass to the 35 first fractioning tower from which vapors of heavy gasoline pass over to a condenser. Vapors of gas oil and kerosene, however, are thrown back in the first fractionating tower and the mixed liquid from the bottom of the first fractionating tower is collected and pumped through a second pipe still where the kerosene is vaporized. From the second pipe still, the vapors pass to a second fractionating tower in which 40 the gas oil is thrown back, the kerosene vapors passing over into a condenser. Liquid gas oil from the bottom of the second fractionating tower passes through a third pipe still in which it is heated to cracking temperature while under pressure. From the third pipe still vapors under 45 pressure pass to a cracking and separating chamber where the cracking occurs and heavy bottoms are separated from the gases and vapors of the cracking step. These gases and vapors then pass through a reducing valve into the topping tower where their contained heat is chiefly instrumental in driving off the light gasoline from the preheated crude which has been preheated in a heat interchanger by heat from the fuel oil. Vapors from the topping tower pass to a 50 condenser for light gasoline.

The second still encountered by the oil is heated by the flue gases from the first and third stills, thus economizing fuel.

65 By the method and apparatus previously described, it is possible to distil and crack a given crude petroleum with a minimum expenditure for fuel. When using only fuel oil in addition to the waste gases from the process, the number of barrels of fuel oil required including fuel for pumping and so forth, is approximately five per cent of the number of barrels of crude introduced into the system. The labor costs in treating crude petroleum according to the present invention are also low and the investment is moderate. Fur-

thermore, the products formed yield the highest return from a given quantity of oil such as Kansas crude in the usual state of the market for refined petroleum products.

The present invention is not in general limited 80 to particular forms or types of apparatus for performing the functions set out herein. In particular, it is not limited to both cracking the oil from the third still and separating out heavy bottoms in a single cylinder or tower. 85

Having now described our invention and in what manner the same is to be performed, we claim—

1. The process of refining crude oils, which comprises topping the oil to be treated to remove 90 light gasoline, passing the topped oil through a heating zone to vaporize heavy gasoline, kerosene and gas oil constituents therefrom, fractionally condensing the resulting vapors whereby said heavy gasoline is recovered separately from a 95 kerosene-gas oil condensate, heating the condensate containing kerosene and gas oil to vaporize said kerosene and separately recover the same, cracking said gas oil under superatmospheric pressure to produce lighter oils therefrom and 100 passing the vapors formed in said cracking through said crude oil to carry out said topping.

2. The process of refining crude petroleum which comprises cracking a gas oil under superatmospheric pressure and high temperature to 105 produce lower boiling vapors therefrom, pre-heating crude petroleum then topping the same by contacting it with said vapors, heating the resulting topped petroleum to vaporize heavy gasoline, kerosene and gas oil therefrom, separately 110 recovering said heavy gasoline by condensing out said kerosene and gas oil constituents from the mixture of vapors resulting from said heating, vaporizing the kerosene from the resulting mixture of kerosene and gas oil condensate and using 115 the gas oil from the mixture in the said cracking.

3. The process of fractionally distilling crude mineral oils, which comprises passing a gas oil under superatmospheric pressure through a heating zone and into a cracking zone, heating the 120 said gas oil to a high temperature and maintaining the same under a superatmospheric pressure in said zones, passing vapors formed in said cracking zone into contact with crude oil to be distilled whereby the light gasoline content of 125 said crude oil is removed and the heavier fractions of said vapors are condensed, heating the resulting mixture of topped crude oil and said heavier fractions of cracked oil to a temperature sufficient to vaporize gas oil and lighter oils contained therein, separating the gas oil from said lighter oils and passing it into said heating zone. 130

4. The process of fractionating crude petroleum oils, which comprises preheating the crude oil to be fractionated, vaporizing light gasoline therefrom, heating the topped crude oil to a temperature sufficient to distil off all remaining fractions lighter than the fuel oil fraction whereby said fuel oil is separated from the distilled fractions, passing said fuel oil while hot into heat exchange 140 relation with said crude oil to perform said pre-heating, fractionally condensing said distilled fractions into heavy gasoline and a mixture of kerosene and gas oil fractions, separating the gas oil from the kerosene in said mixture, cracking 145 the gas oil fraction under superatmospheric pressure at a high temperature, and passing the vapors therefrom into contact with said preheated crude oil to vaporize said light gasoline.

5. The process of fractionating crude petrole-

150

um oils, which comprises passing the oil to be treated in heat exchange relation with vapors from a cracking chamber whereby a mixture of reflux condensate and topped crude oil is produced passing said mixture through a heating zone and into a vaporizing zone where a liquid fuel oil residue separates, withdrawing vapors from said vaporizing zone, separating a gas oil fraction therefrom, heating said fraction to a cracking temperature under superatmospheric pressure and passing it into said cracking chamber.

6. An apparatus for treating oils, comprising a closed series of units, each unit of the series comprising an oil heater, a vapor fractionating tower and a final condenser, means for passing oil from the fractionating tower of each unit into the oil heater of the next succeeding unit, and means for introducing oil to be treated into the fractionating tower of one of said units.

7. In the process of fractionally distilling crude petroleum oils in which the crude oil to be distilled is topped by being passed in direct contact with hot cracked vapors in a dephlegmating zone and from which a mixture of topped crude oil and reflux condensate is withdrawn, the improvement which comprises, further heating said mixture while hot by passing it through a confined heating zone in which the mixture is heated to a temperature adapted to vaporize substantial portions thereof, discharging the thus heated mixture into a vapor-liquid separating zone, withdrawing unvaporized residue oil from said separating zone, cracking a portion of the constituents vaporized from said mixture by heating the same to a high temperature while conducting the same through a confined heating zone, and contacting the hot cracked vapors resulting from said cracking with said crude oil in said dephlegmating zone.

8. The combined process of fractionating and cracking petroleum oils, which comprises heating crude oil containing gasoline and introducing it into a tower in contact with hot cracked vapors containing gasoline constituents, conducting the gasoline vapors from said tower for condensation, passing unvaporized oil and condensate from said tower through a heating zone and then into an enlarged chamber wherein portions of said mixture are vaporized, passing vapors from said chamber into a second fractionating tower wherein a reflux condensate is produced, heating and cracking condensate from said second tower to produce hot cracked vapors therefrom, and passing the resulting cracked vapors into said first tower to be contacted with said crude oil.

60

65

70

75

9. The process of treating petroleum, which comprises distilling crude oil containing gasoline in a zone of relatively low pressure, drawing off the lighter components of said oil in the form of vapor from said zone, pumping the heavier liquid components of said oil from said zone and forcing the same in a restricted stream through a heating zone and then into a second vaporizing zone, heating the said liquid components to a temperature sufficient to effect vaporization of only the lighter constituents of said liquid upon being discharged into said second zone, removing vapors from said second zone to produce distillates therefrom, forcing distillate formed from said vapors under superatmospheric pressure through a cracking still and then into an enlarged chamber, conducting relatively light vapors from said chamber into the first mentioned zone, and passing them therein countercurrent to said crude oil.

10. The process of treating oils, which comprises cracking a petroleum distillate by heating it to a high temperature under superatmospheric pressure in a cracking zone, passing cracked products from said zone into a zone of lower pressure wherein said cracked products are mixed and intimately contacted with crude oil containing gasoline, thereby to cool said products and vaporize the lower boiling constituents of said crude oil, subjecting the combined vapors to refluxing and final condensation, fractionating the mixture of topped crude oil and high boiling point cracked products from said low pressure zone into fuel oil bottoms and a plurality of distillates having different boiling points, and using one of said distillates for cracking in said cracking zone.

11. The process of refining crude petroleum, which comprises cracking a gas oil to produce lower boiling point vapors therefrom, topping crude petroleum by contacting the same with said vapors, heating the resulting topped petroleum to vaporize heavy gasoline, kerosene and gas oil therefrom, separately recovering said heavy gasoline by condensing out said kerosene and said gas oil constituents from the mixtures of vapors resulting from said heating, vaporizing the kerosene from the resulting mixture of kerosene and gas oil condensate, using the gas oil from the said mixture in said cracking, and utilizing the waste heat from heating said gas oil and said topped petroleum as the sole heating means for vaporizing said kerosene.
